CLAIM

The ornamental design for a motorcycle ride bell mount, as shown and described.

DESCRIPTION

FIG. 1 is a frontal perspective view of a preferred embodiment of my motorcycle ride bell mount;

FIG. 2 is a front plan view thereof, the rear view comprising a mirror image thereof;

FIG. 3 is a right side elevational view thereof, taken from a position to the right of FIG. 1;

FIG. 4 is a left right side elevational view thereof, taken from a position to the left of FIG. 2;

FIG. 5 is a top plan view thereof; and,

FIG. 6 is a bottom plan view thereof.
